CLARK E. WEAVER, OF KANSAS CITY, MISSOURI.

DOOR VENTILATING MECHANISM.

Application filed May 12, 1928. Serial No. 277,380.

My invention relates to improvements in door ventilating mechanisms. It relates particularly to structures in which a door is provided with a ventilating opening therethrough, and having a closure hinged thereto for closing the opening.

One of the objects of my invention is to provide novel mechanism by which the door in moving to the open position will move the closure toward the closed position, if the closure is open, but which is inoperative if the closure is closed, and which permits the closure to be freely opened or closed when the door is closed.

A further object of my invention is to provide a novel mechanism of the kind described, which is simple, cheap, durable, strong, not likely to get out of order, which is efficient in operation, and which may be readily applied to door structures of this character which are already built or in use.

The novel features of my invention are hereinafter fully described and claimed.

In the accompanying drawing, which illustrates the preferred embodiment of my invention,

Fig. 1 is a top view, partly broken away and partly in section of my improved mechanism shown attached to a door.

Fig. 2 is a front elevation, partly broken away and partly in section of the same, the closure being closed.

Fig. 3 is an enlarged vertical cross section through the screw and nut, as disposed when the door is closed and the closure is open.

Fig. 4 is a vertical cross section of the closure shown open and parts connected therewith.

Fig. 5 is an enlarged section through the screw and nut, shown in the positions occupied by them when the door is open.

Fig. 6 is a perspective view of a portion of my improved mechanism.

Similar reference characters designate similar parts in the different views.

1 designates a door hinged in the usual manner to a door frame 2, and provided with an opening 3 therethrough, for ventilation purposes, the door having hinged to it adjacent to the lower edge of the opening 3, on the axis 4, Fig. 4, a closure 5, which is adapted to be swung from the closed position, Fig. 2, to the inclined position shown in Figs. 1 and 4.

55 The closure 5 is provided with the usual

overlapping slats 6 arranged to fold over each other when the closure is shut.

7 designates one wall in which the frame 2 is mounted, and 8 designates another wall at right angles thereto and at the right of 60 and closely adjacent to the frame 2.

With a wall 8 so close to the door, if the closure 5 should be open when the door 1 is swung to the position shown in dotted lines in Fig. 1, the closure would strike the 65 wall and so might mar the wall or damage the closure mechanism. My invention is designed to prevent such marring or damaging, by having the opening movement of the door serve to swing the closure 5 toward the 70 closed position, or to the fully closed position, as may be required.

To effect such closing of the closure with the opening movement of the door, I provide means which connects the door with the 75 frame and with the closure, and which, preferably comprises the following described parts.

A member 9, which may be a nut, is oscillatably mounted on a vertical axis in a recess 10 in the upper edge of the door 1. The member 9 has a horizontal arm 11 above the door, said arm being pivoted by a vertical pin 12 to one end of a horizontal link 13, disposed between the door 1 and the top of the frame 2 and pivoted by a vertical pin 14 to the under side of the top of the door frame 2.

Rotatably fitted in the nut 9 is a screw 15 which is soldered or brazed, or otherwise integrally connected with and forms a part of 80 a link 16, the free end of which is pivoted by a pin 17 to one end of a link 18, the other end of which is pivoted by a pin 19 to the upper edge of the closure 5.

When the door 1 is closed, and the closure 95 is swung to and from the open position, the links 16 and 18 will fold and unfold, and in the folded position will be between the upper edge of the closure 5 and the portion of the door over the opening 3, as shown in Fig. 2. 100 When the closure 5 is open, the links 16 and 18 will be extended, as shown in Figs. 1, 3, 4 and 6.

As the link 16 swings toward the folded position, Fig. 2, the screw 15, forming a part 105 thereof, will unscrew and lower in the nut 9, and as the closure moves toward the open position, the screw 15 will screw upwardly into the nut 9.

In order that the opening of the door to 110

the position shown in dotted lines in Fig. 1, will swing the closure 5 to or toward the closed position, to prevent the closure striking the wall 8, there is fitted in the nut 9 above the screw 15, a stop screw or abutment 20, which is vertically adjustable in the nut.

When the door is closed and the closure is swung to the fully open position, shown in Figs. 1, 3 and 4, the screw 15 will be in contact with the lower end of the stop screw 20, as shown. If now the door 1 is opened, and the closure is open, the opening movement of the door, by means of the link 13, which is pivoted to the frame 2 and to the arm 11, will turn the nut 9 in the recess 10, in a direction such as will tend to screw the nut further onto the screw 15, but as the latter is in contact with the stop screw 20, the screw 15 will be forced to turn with the nut, thereby swinging the link 16 inwardly, and by means of the link 18 drawing the closure 5 to the closed position, or toward the closed position, depending on the position of the screw 20 in the nut.

25 When the door is closed, the closure 5 may be swung to and from the open position, without the movement of the screw 15 being interfered with by the stop screw 20, as in closing the closure, when the door is closed, the screw 15 draws away from the stop screw 20, and only contacts therewith when the closure is open.

By adjustment of the screw 20, the opening movement of the closure 5 may be varied in extent.

35 I do not limit my invention to the structure shown and described, as many modifications, within the scope of the appended claims, may be made without departing from the spirit of my invention.

40 What I claim is:—

1. In a door ventilating mechanism, the combination with a door frame, a door hinged thereto having a ventilating opening therethrough, and a closure for said opening movable on said door to and from a closed position, of means connecting the door with the frame and closure and actuated by the door in opening for moving the closure toward the closed position, in case the closure is in the open position.

55 2. In a door ventilating mechanism, the combination with a door frame, a door hinged thereto having a ventilating opening therethrough, and a closure for said opening hinged to said door, of means connecting the door with the frame and closure and actuated by the door in opening for swinging the closure toward the closed position, if the closure is in the open position.

60 3. In a door ventilating mechanism, the combination with a door frame, a door hinged thereto having a ventilating opening therethrough, and a closure for said opening

movable to and from the closed position, of a member oscillatable on said door and having an arm, a link pivoted to said arm and to said frame, and means actuated by said member on the opening movement of said door for moving the closure toward the closed position, if the closure is in the open position.

4. In a door ventilating mechanism, the combination with a door frame, a door hinged thereto having a ventilating opening therethrough, and a closure for said opening movable on said door to and from the closed position, of a member oscillatable on said door and having an arm, a link pivoted to said frame and to said arm, a link pivoted to said closure, and means connecting said last named link with said member by which the door in opening will move the closure toward the closed position, if the closure is in the open position.

5. In a door ventilating mechanism, the combination with a door frame, a door hinged thereto having a ventilating opening therethrough, and a closure for said opening, of a member oscillatable on said door and having an arm, a link pivoted to said arm and to said frame, two links pivoted to each other, one being pivoted to said closure and the other having pivoted and threaded engagement with said oscillatable member, and stop means for limiting the relative turning movement between said threaded link and oscillatable member, whereby the door in opening will move the closure toward the closed position, if the closure is in the open position.

6. In a door ventilating mechanism, the combination with a door frame, a door hinged thereto having a ventilating opening therethrough, and a closure for said opening, of a nut oscillatable on said door and having an arm, a link pivoted to said frame and to said arm, two links pivoted to each other, one being pivoted to said closure and the other having a screw pivotally fitted in said nut, and stop means for limiting the turning of said screw in said nut arranged so that the door in opening will move said closure toward the closed position, if the closure is in the open position.

7. In a door ventilating mechanism, the combination with a door frame, a door hinged thereto having a ventilating opening therethrough, and a closure for said opening, of a nut oscillatable on said door and having an arm, a link pivoted to said arm and to said frame, two links pivoted to each other, one being pivoted to said closure and the other having a screw pivotally fitted in said nut, and a stop screw adjustably mounted in said nut and adapted to be struck by the other screw and limit the turning thereof in said nut when the door is opened, if

the closure is in the open position, and thereby moving the closure toward the closed position.

8. In a door ventilating mechanism, the combination with a door frame, a door hinged thereto having an opening therethrough, and a closure hinged to the door for closing said opening, of means connect-

ing the door with said frame and with said closure by which the door in opening will ¹⁰ swing the closure toward the closed position, if the closure is open, and inoperative to move the closure if the closure is closed.

In testimony whereof I have signed my name to this specification.

CLARK E. WEAVER.
